VEHICLE BODY CONSTRUCTION

Irving B. Cooper, Allendale, N. J.

Application April 27, 1938, Serial No. 204,543

2 Claims. (CL 296—22)

In my Patent No. 2,107,854 I have disclosed certain improvements in the elongated frame structure of a car body (as of a so-called diner) of the class intended to occupy a given site indefinitely but which, in order to attain a particular position at the site, has to be moved over rough ground, the improvements therein set forth being of such nature as peculiarly to strengthen the structure without presence of underneath trussing which would interfere with the movements of the car.

It is desired to provide a car of this class which will have booths arranged along one wall, as its front wall, hence involving increasing its length so as to include an appreciable number of the booths, and which will have a central door in said wall. This means that there is to be taken into account not only the greater dead weight (with consequently greater potential live weight) in proportion of the length of the car but the break in said wall incident to the door in constructing that part of the frame structure which includes said wall so that said structure will be amply rigid and strong—that is to say, not only generally or with respect to the whole length of said part of the frame structure, but preferably also with respect to each portion or section thereof which flanks the doorway.

The present invention therefore consists in a frame structure of the class referred to which has these considerations in view.

In the drawing,

Fig. 1 is an isometric view of the improved frame structure as seen from the front, and, Fig. 2 is a diagrammatic plan of the car with the roof removed.

The elements of the frame structure are of steel and, as in my said patented construction, wherever they are stated or shown to be contiguous to each other within any wall of the structure or at the junctures of walls they are rigidly connected together, as by welding. And in so far as the following elements are concerned the frame structure is or may be all substantially the same as in said patented construction, to wit: The cross-beams 1; the rails 2, 3, 4, 5 and 6 of the floor-frame; the uprights which support the roof, being columns 7 and posts 8; the horizontal rail 9 at one end; the downwardly converging bars or rails 13 at the back; and the rails 15—16, arches 17 and panel 18 of the roof-frame. In the present case there is a single upstanding grid 19 affixed to rail 5 and having appreciable effect to reinforce the floor structure; it supports a counter 20 and adjacent thereto are

seats or stools 21. Instead of at the front there being a single horizontal rail extending from one remote end upright or column 7 to the other and because of the doorway 22 left existing between the two adjacent uprights or mid-posts of the two series of front uprights there are two such rails, 23, respectively extending from said columns to said mid-posts and demarking the lower sides of the window openings at 24. And instead of the rail opposite to end rail 9 being continuous there are two aligned rails 9a affording a doorway 25. Further, there are cross-beams 1a between the cross-beams 1 of the floor-frame. Referring, now, to the improvements herein claimed:

Means, here at the front part of the structure, forms therewith a truss, such means including a pair of tie-rails 26 which converge downwardly from respectively substantially the junctures a of the rails 23 and the remote end uprights or columns 7 of the two series of uprights to, respectively, substantially the junctures b of rail 2 and the innermost end uprights or mid-posts 8 of the two series, and such means here also and preferably including two other tie rails 26' which converge downwardly from substantially the junctures a to points c of the rail 2 which are about midway between points b and said remote end uprights. For bracing each remote end upright against the pull of the corresponding tie rails there is a brace rail 27 extending from juncture a to a point d between point c and such upright. Thus the structure at its front part exists with a truss active with respect to the whole length of said part.

Due to the increased load to be independently imposed on each section of the front part of the structure defined by rails 2, 15 and a series of uprights such section should within itself be reinforced, which to some extent is accomplished by the rail 26'. But preferably from substantially the juncture of the corresponding innermost end upright or mid-post 8 with rail 23 to substantially the point c another tie rail 28 extends to coact with rail 26' in the forming of a truss.

The first-mentioned trussing may be augmented, further, by tie-rails 29 connecting the junctures b respectively with the junctures e of the rails 23 with posts lateral of the mid-posts.

At 30, each side of the doorway and at the front of the frame structure, are indicated partitions defining the mentioned booths, representing augmented dead load at such part of the structure and hence potential live load. The partition 31 defines an apartment at the back of the struc-

ture to serve as a retiring room and at 32 are the work-counters.

Having thus fully described my invention what I claim is:

- 5 1. In combination, with an elongated vehicle body frame structure comprising floor and roof frames and means to support the roof frame on the floor frame including uprights arranged in a single row in two spaced substantially equal-length series substantially coincident with corresponding long sides of the two frames and respectively extending from substantially the ends of the frame structure to near its mid-length and spaced alined horizontal rails traversing all 10 the uprights of the respective series and each rigidly secured to the end uprights of the corresponding series, of means to reinforce said structure including tie-rails rigidly secured thereto approximately at the junctures of the horizontal rails with the remote end uprights of the two series and converging downwardly to and

respectively rigidly secured to said structure approximately at the junctures of the adjacent end uprights of the two series with the floor frame, said last-named means also including in association with each series of uprights downwardly converging equal-length tie-rails respectively connected at their upper or remote ends to said structure at the junctures of the corresponding horizontal rails with the end uprights of such series and also respectively rigidly connected at their lower or adjoining ends to said structure in substantial coincidence with the floor frame. 5 10

2. The combination set forth in claim 1 characterized by said last-named means also including in association with each series of uprights another and shorter tie-rail rigidly secured to said structure at the corresponding first-named juncture and inclined downwardly therefrom and rigidly secured at its lower end to said structure in substantial coincidence with said floor frame. 15 20
